BELT SANDING MACHINE

Gene De Mambro and Linsly G. Brown, Jamestown, N. Y., assignors to The Carborundum Company, Niagara Falls, N. Y., a corporation of Delaware

Application September 12, 1955, Serial No. 533,652

6 Claims. (Cl. 51—141)

This invention relates to belt sanding machines. It is particularly directed to such machines which are designed for sanding wood although they may be employed for sanding other materials.

One object of the invention is to provide a belt sanding machine so constructed that sanding may be done on both sides of the long stretches of the belt between the pulleys which carry it. Another object of the invention is to provide a belt sanding machine with work tables along the long stretches of the belt which are so constructed that the table or tables may be tilted without movement of the top line of the inner side of the table adjacent the abrasive belt. Another object of the invention is to provide such a machine wherein the abrasive belt is supported throughout the long stretches by a serrated contact or supporting belt. Another object of the invention is to provide such a machine wherein sanding can be done at one end of the machine where the abrasive belt passes over a serrated contact wheel. Other objects of the invention will be apparent from the description which follows:

The invention has been illustrated with drawings wherein:

Figure 1 is a plan view of one embodiment of the invention;

Figure 2 is a front elevation of the same embodiment of the invention;

Figure 3 is a section along the line 3—3 of Figure 1;

Figure 4 is a front elevation of one end of the machine illustrating a second embodiment of the invention; and

Figure 5 is a perspective view of a carrier belt adapted for use in the machine.

Referring now to the drawings, the machine comprises a base having a front face 1 and a back face 2 reinforced by ribs 3 extending within the cavity provided by the two faces and by I-beam 53.

Suitably mounted on one end of the base is an electric motor 4 for driving the belts. The upper end of the motor carries a drive pulley 5 about which the carrier belt 6 and the abrasive belt 7 travel. The carrier belt travels around a second or idler pulley 8 and the abrasive belt extends to and travels around a third pulley 9 which is desirably serrated to provide a "contact wheel." The carrier belt 6 is backed up by platens 51 and 52.

Suitably attached to the faces 1 and 2 of the base are table supports 10 which are vertically adjustable by rotation of screws 11 in bearings 12 which are attached to the faces of the base. The rotation of the screws 11 is effectuated by movement of the hand wheel 13. The vertical movement of the supports is guided by pins 14 extending through bearings 15 which are attached to the faces of the base.

Attached to the under side of the side work tables 16 are elements 17 provided with arcuate slots 18 for tilting the side work tables. Elements 17 are supported by roller pins, which are desirably in the form of cam followers 19 which extend through slots 18. The angular position of the side work tables is fixed by tightening of the

2

wheels 20 which lock the elements 17 in the desired position.

An important feature of the invention resides in the fact that the slots 18 are described as arcs about the upper and inner sides 21 of the side work tables 16. Consequently, when the tables 16 are tilted the line extending along the upper and inner edge 21 of the work table does not move and the inner end of the work table is therefore at a fixed position with respect to the abrasive belt 7 regardless of the extent to which the work tables 16 are tilted.

A second feature of the invention is the provision of an idler pulley 8 for the carrier belt 6 which is at least as large in diameter, and preferably of the same diameter as the drive pulley 5. The pulley 8 is mounted on spindle 22 riding in suitable bearings in supporting element 23 which in turn is attached to the base by a bracket 24 provided with pin 25 which forms an axis about which the spindle for the pulley may be tilted. Adjustment 20 of the inclination of the vertical axis of the pulley 8 is made by movement of the screw 26 in the threaded bearing 27 by turning the hand wheel 28. When the pulley has been properly positioned it may be locked in place by turning the hand nut 29 which bears on the pin 26 and prevents rotation thereof. Adjustment of the inclination of the spindle 22 is necessary in order to provide proper tracking of the supporting or carrier belt 6.

Tensioning of the carrier belt 6 is provided by moving the bracket 24 in a horizontal plane by revolution of 30 the screw 30 in the threaded bearing 31 which is fastened to a sliding plate on gibbed dovetailed ways, fastened to the base plate. The rotation of the screw is effected by turning the hand wheel 32 which causes rotation of the screw 30 through bevel gears not shown in the drawings.

35 The third pulley or contact wheel 9 is mounted on sealed ball bearings on a spindle 33 positioned in a suitable bushing attached to a pivot mounted on a dovetailed slide on the base. The spindle with its pulley or contact wheel is therefore removable by simply lifting the assembly of spindle and contact wheel as a unit out of the bushing. This feature makes it possible to change contact wheels and thus substitute wheels of different diameters by merely lifting out the assembly and replacing it with another having a wheel of the desired diameter. 40 Adjustment of the position of the spindle 33 along a horizontal line to tension the belt is made by rotating the screw 34 by turning hand wheel 35. Screw 34 is suitably carried within slide element 36 mounted on the vertical base plate.

45 Adjustment of the position of the spindle 33 along a horizontal line to tension the belt is made by rotating the screw 34 by turning hand wheel 35. Screw 34 is suitably carried within slide element 36 mounted on the vertical base plate.

50 Tracking of the abrasive belt is effected by changing the vertical position of the spindle 33 by rotation of the screw 37 brought about by turning hand knob 38, in a manner similar to that described with respect to the idler pulley 8.

55 A third or end work table 39 may be provided for sanding at the end of the machine where the abrasive belt travels about the contact wheel 9. In the embodiment illustrated in Figures 1 and 2 the table 39 is shown as being fixed in position. This table may also be made 60 both adjustable in a vertical plane and tiltable by suitable means as illustrated in Figure 4 wherein the support 40 for the table is adjustable vertically by rotation of the hand wheel 41 which results in raising or lowering the table by movement along conventional gibbs. Tilting of the 65 table is effected in the manner described with respect to the other tables by loosening the locking nut 42 which fastens the table in position as it is tilted by movement through the slot 43 as in the case of the side tables.

The end table is also tiltable without movement of the upper and inner edge 44 of the table by reason of the fact that the slot 43 is described as an arc about this upper inner edge 44 as a center. In the embodiment

illustrated in Figure 4 the belt is tensioned by rotating the hand wheel 45 which causes movement in a horizontal plane of the pivoted bracket 46 for the contact wheel spindle 33.

Still another feature of the invention is the employment of the carrier belt 6 a small portion of which is shown in perspective in Figure 5. The belt has a backing 47, which is desirably of a strong cloth such as woven duck, to which is cemented a rubber or synthetic rubber portion having ridges 48 and depressions 49. Neoprene has been found to be suitable for this rubber-like layer. Since the carrier belt travels about the pulleys 5 and 8 whereas the abrasive belt stretches over the carrier belt and around pulley 5 but continues over around contact wheel 9, the relative position of the abrasive belt with respect to the carrier belt is constantly changing. This assists in removing detritus from the belt and is important because of the fact that the belt is used at three different stations and consequently gets very severe treatment.

Machines constructed in accordance with this invention have a great advantage over the machines of the prior art. By making pulleys 5 and 8 of substantially the same diameter for carrying the carrier or supporting belt 6 it is possible to use both of the long stretches of the abrasive belt where the carrier belt supports it and by extending the abrasive belt around the contact wheel 9 and making that pulley or contact wheel of smaller diameter than the other two, or pair of pulleys, it is possible to provide a third work station. Consequently, a very considerable amount of work can be done on this one machine simultaneously. In actual use it has been shown that the output of a machine made in accordance with this invention is several times that of machines heretofore employed.

While we have shown the machine with two side work tables both of which are adjustable both vertically and angularly it is of course within the purview of the invention to provide this feature with respect to only one of these side belts, the other being fixed in instances where the work is of such character that it is unnecessary to tilt or vertically adjust the table.

Similarly, we have shown the end work table 39 as being either fixed in position or adjustable both vertically and angularly. It is of course feasible to have this table either fixed or adjustable vertically only. One important advantage of the vertical adjustment comes from the fact that it is possible to use the full width of a wide abrasive belt even though the work is comparatively narrow. When such material is being worked any or all of the tables may be lowered to employ only the lower part of the belt and as that part becomes dulled the tables may be adjusted vertically so that the work will be applied at fresh surfaces of the abrasive belt.

While we have illustrated our invention by reference to certain drawings and have described certain constructions it is to be understood that the invention is not to be limited to the specific structures and embodiments illustrated and described herein but rather is to be considered of the scope of the appended claims.

We claim:

1. A belt sander comprising a base, a pair of spindles mounted on said base, a pair of pulleys mounted on said spindles, respectively, for rotation about their longitudinal axes, said longitudinal axes lying in one plane, means for rotating one of said pulleys, an endless backup belt mounted to travel around said pulleys, said pulleys having substantially identical diameters whereby the two reaches of said backup belt are in parallelism, a third spindle supported from said base remote from said pair of spindles, a third pulley mounted on said third spindle for rotation about its longitudinal axis, the longitudinal axis of said third pulley lying in said one plane, an endless abrasive belt mounted to travel about one of said pair of pulleys in superposed engagement with said backup belt and about said third pulley, said third pulley

having a diameter smaller than that of said pair of pulleys, whereby said abrasive belt is in continuous superposed engagement with said backup belt along both reaches of said backup belt between said pair of pulleys, 5 means for inclining the axis of one pulley of said pair in said plane and independent means for inclining the axis of said third pulley in said plane to control tracking of the backup belt and of the abrasive belt respectively, means for moving one pulley of said pair and independent means for moving said third pulley toward and away from said remaining pulley respectively, to adjust the tension on the backup belt and on the abrasive belt respectively, and work tables mounted on said base on each side thereof adjacent the two reaches of said abrasive belt and between said pair of pulleys.

2. A belt sander as in claim 1 including a pair of parallel platens mounted on said base and disposed, respectively, along and between the reaches of the backup belt to limit the movement of each reach of said backup belt and to support said backup belt.

3. A belt sander as in claim 1 wherein said endless backup belt has a serrated surface disposed to engage against the confronting surface of the abrasive belt.

4. A belt sander as in claim 1 wherein said third 25 pulley is secured to said third spindle, and the assembly of said third spindle and third pulley is removable from said base as a unit.

5. A belt sander comprising a base, a pair of spindles mounted on said base, a pair of pulleys mounted on said 30 spindles, respectively, for rotation about their longitudinal axes, said longitudinal axes lying in one plane, means for rotating one of said pulleys, an endless backup belt mounted to travel around said pulleys, a third spindle supported from said base remote from said pair of spindles, a third pulley mounted on said third spindle for rotation about its longitudinal axis, the longitudinal axis of said third pulley lying in said one plane, an endless abrasive belt mounted to travel about one of said 35 pair of pulleys in superposed engagement with said backup belt and about said third pulley, the diameter of the pulley in said pair that is in intermediate position between said third pulley and the other pulley of said pair being at least as great as the diameter of said third pulley whereby said abrasive belt is maintained in continuous superposed engagement with said backup belt along both reaches of said backup belt between said 40 pair of pulleys, means for inclining the axis of one pulley of said pair in said plane and independent means for inclining the axis of said third pulley in said plane to control tracking of the backup belt and of the abrasive belt respectively, means for moving one pulley of said pair and independent means for moving said third pulley toward and away from said remaining pulley to adjust the tension on the backup belt and on the abrasive belt, 45 respectively, and work tables mounted on said base on each side thereof adjacent the two reaches of said abrasive belt between said pair of pulleys.

6. A belt sander as in claim 5 and including support members for said work tables mounted on said base, 50 said members being formed with arcuate slots that are formed about a center along the top inside edge of the associated work table, roller pins dependent from said work tables and disposed to slide in said slots, and means to secure said tables in any adjusted, inclined position.
